UNITED STATES PATENT OFFICE.

GEORGE W. SCHRAEDER, OF UTICA, NEW YORK.

SEWING-MACHINE.

1,273,935

Specification of Letters Patent. Patented July 30, 1918.

Application filed October 6, 1917. Serial No. 195,104.

To all whom it may concern:

Be it known that I, GEORGE W. SCHRAEDER, a citizen of the United States, residing at Utica, in the county of Oneida and State of New York, have invented certain new and 5 useful Improvements in Sewing-Machines, of which the following is a specification, reference being had to the accompanying drawings.

10 This invention relates to certain improvements in sewing machines and has relation more particularly to a sewing machine employed in the production or repair of shoes, and it is an object of the invention to provide a novel and improved device for producing a channel or groove in the sole of a shoe wherein the stitches are received.

It is also an object of the invention to 20 provide a novel and improved device or attachment for cutting channels in a shoe sole or the like which may be removed and applied with convenience and facility.

The invention consists in the details of 25 construction and in the combination and arrangement of the several parts of my improved sewing machine wherein certain important advantages are attained and the device rendered simpler, less expensive and otherwise more convenient and advantageous for use, 30 as will be hereinafter more fully set forth.

The novel features of my invention will hereinafter be definitely claimed.

In order that my invention may be the better understood I will now proceed to describe 35 the same with reference to the accompanying drawings wherein:

Figure 1 is a view in elevation of a work support having an attachment constructed in accordance with an embodiment of my invention applied thereto, the adjacent portion 40 of the sewing machine being diagrammatically indicated by dotted lines;

Fig. 2 is a view in top plan of a work support having my improved attachment;

45 Fig. 3 is a sectional view taken substantially on the line 3—3 of Fig. 2;

Fig. 4 is a sectional view taken substantially on the line 4—4 of Fig. 2;

50 Fig. 5 is a view in side elevation of the cutting attachment as herein embodied unapplied; and

Fig. 6 is a view in side elevation of a further embodiment of my improved attachment.

55 As disclosed in the accompanying draw-

ings S denotes a work support adapted to be mounted in applied position upon the frame of the sewing machine and in proper position relative to the needle of the sewing machine mechanism.

The forward or outer end portion of the support S at substantially its transverse center is provided with a recess 1 in which extends the block 2 depending from the outer end portion of the plate P. The plate P is 60 disposed longitudinally of the support S and is arranged at substantially the transverse center thereof. It is also preferred that the side wall of the block 2 and the adjacent portion of the side walls of the plate P be 65 inwardly and downwardly beveled as indicated at 3. The plate P and the block 2 depending therefrom extend beyond the outer end of the support S and have produced therethrough the needle slot 4 and the 70 upper portion of said slot 4 at one end is open at the side of the plate P as indicated at 5, to afford a recess.

Snugly fitting within the recess 5 is an 75 arm 6 having one end portion provided with the depending lug 7. The inner face of the lug 7 is beveled as indicated at 8 to firmly contact with the adjacent beveled face 3 of the head 2 below the recess 5 whereby the arm 6 is held against rocking or tilting 80 movement. It will also be self-evident that the lug 7 coacts with a beveled face of the head 2 to hold the arm 6 against endwise movement to effectually brace the same 85 against the strain imposed thereupon during 90 the working operation and which strain is considerable in view of the fact that the cutting member 9, to be hereinafter more particularly referred to, acts directly upon the sole. The opposite end of the arm 6, when 95 applied within the recess 5 terminates substantially flush with the adjacent end of the needle slot 4 and said inner end portion of the arm 6 is provided with the upstanding cutting member 9 preferably formed integral therewith and which member serves to

properly cut a thread receiving channel in the sole of a shoe as the work is passed over the outer end of the plate during a sewing operation. The outer end of the plate P is 100 provided with a threaded opening 10 in communication with the recess 5 and through which opening 10 is disposed a binding screw 11. The inner end of the screw 11 seats within a recess 12 produced 105

in the adjacent face of the arm 6. By this arrangement it will be at once self evident that the arm 6 is effectively locked in applied position yet can be readily removed 5 when desired.

The operation of my improved attachment is believed to be clearly apparent to those skilled in the art to which my invention relates and although it may be well to 10 state that a particular advantage of my present invention is the provision of means whereby the arm 6 may be readily applied when it is desired to cut a channel within the sole of a shoe or whereby said attachment 15 may be removed. When a rubber or composition sole is being applied to a shoe it is not necessary that a groove or channel be cut therein, therefore when a rubber or composition sole is being used the attachment 20 as particularly illustrated in Fig. 5 is removed and in lieu thereof is applied the attachment particularly illustrated in Fig. 6. This attachment comprises an arm 6' adapted to snugly fit within the recess 5 25 and has one end portion provided with the depending lug 7'. The inner face of the lug 7' is beveled as indicated at 8' to firmly contact with the adjacent beveled face 3 of the head 2 below the recess 5 whereby the 30 arm 6' is held against rocking or tilting movement. The opposite end of the arm 6' when applied within the recess 5 terminates substantially flush with the adjacent end of the needle slot 4 in the same manner as has 35 been hereinbefore set forth relative to the arm 6. The upper face of the arm 6' is flat and unobstructed so that no cutting action or other effect is had upon a rubber or composition sole. A face of the arm 6' is provided with a recess 12' with which is adapted 40 to co-act the screw 11 as has hereinbefore been set forth relative to the arm 6.

An especial advantage of my present invention is the fact that the attachment as 45 particularly illustrated in Fig. 5 may be removed and the attachment as particularly illustrated in Fig. 6 may be applied within substantially one-half a minute or vice versa whereas in the shoe sewing machines now

generally employed it requires from five to 50 10 minutes to change the channel cutting attachment.

From the foregoing description, it is thought to be obvious that a sewing machine constructed in accordance with my invention 55 is particularly well adapted for use by reason of the convenience and facility with which it may be assembled and operated and it will also be obvious that my invention is susceptible of some change and modification 60 without materially departing from the principles and spirit thereof and for this reason I do not wish to be understood as limiting myself to the precise arrangement and formation of the several parts herein shown in 65 carrying out my invention in practice except as hereinafter claimed.

I claim:

In a sewing machine, a work support provided with a needle slot, said member being provided with an open groove in its outer face in communication with the end portion of the slot in advance of the portion of the slot through which the needle of the sewing machine passes, said groove 70 being in longitudinal alinement with said slot, an arm snugly fitting within the groove and having its inner end substantially flush with the adjacent end of the needle slot, the inner end portion of the arm being provided 75 with an upstanding cutting member, the opposite end portion of the arm being provided with a lug disposed in a direction opposite to the cutting member, the opposed faces of the lug and the working support being correspondingly beveled and in contact one 80 with the other, the bevel of the work support being disposed downwardly and inwardly so that the lug of the arm underlies the support, and a clamping member 85 threaded through the side face of the arm.

In testimony whereof I hereunto affix my signature in the presence of two witnesses.

GEORGE W. SCHRADER.

Witnesses:

F. H. DONALDSON,
JOHN FROMANN.
